UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

DESIGN FOR AN INSTRUMENT-BOARD PANEL.

Application filed July 23, 1927. Serial No. 22,857. Term of patent 3½ years.

To all whom it may concern:

Be it known that I, ARCHER L. KNAPP, a citizen of the United States, residing at Detroit, county of Wayne, State of Michigan, have invented a new, original, and ornamental Design for Instrument-Board Panel, of which the following is a specification, reference being had to the accompanying drawing, forming part thereof.

The figure is a front elevation of a panel for an instrument board, showing my new design.

I claim:

The ornamental design for an instrument board panel, as shown.

In testimony whereof I affix my signature.

ARCHER L. KNAPP.
